UNITED STATES PATENT OFFICE

2,470,762

FOLDING MACHINE

Leo R. Dickenson, Washington, D. C.

Application April 25, 1947, Serial No. 743,906

4 Claims. (Cl. 270—83)

(Granted under the act of March 3, 1883, as
amended April 30, 1928; 370 O. G. 757)

1

The invention described herein may be manufactured and used by or for the Government of the United States for Governmental purposes without the payment to me of any royalty thereon in accordance with the provisions of the act of April 30, 1928 (Ch. 460, 46 Stat. L. 467).

This invention relates to folding machines and more particularly to improvements in sheet folding machines of the drop knife type.

This invention is particularly useful in a conventional sheet folding machine having a plurality of drop knives which operate in succession on a sheet of paper or like material passing through the machine to provide a plurality of folds in the sheet in the production of a signature or folded form. It is, therefore, appropriate to explain the present invention in its application to such machine.

In these conventional folding machines sheets are fed therethrough in succession and from folding station to folding station. The sheet feeding mechanism usually includes moving tapes and rollers as well as the drop knives. All operating parts of the machine are driven by a single motor, usually an electric motor. It frequently happens that a number of sheets accidentally become jammed or balled up in the feeding mechanism for any one of a number of reasons. As a result, much time and effort are wasted in removing the fouled sheets and restoring the machine to normal operation. Fouling of the sheets may also cause damage to the machine and necessitate costly repairs. At the same time, there is a loss in production of signatures by the machine.

This invention provides the folding machine with a device which operates to stop the machine in event a sheet fails to reach proper position at a station below a folding knife and which permits the machine to continue its normal operations as long as sheets are properly passing therethrough.

It is therefore an object of this invention to improve sheet folding machines.

Another object is to provide a sheet folding machine with an automatically operating device for interrupting the operation of the motor which drives the machine in the event a sheet fails to move normally through the machine.

Still another object is to provide sheet folding machines with a safety device which is of relatively simple and rugged construction, is inexpensive to manufacture, is highly efficient for its intended purpose, and will minimize production losses.

Other objects and advantages will be apparent from the following description, the appended

2

claims and the accompanying drawings which illustrate a preferred embodiment of this invention.

Referring to the drawings,

Fig. 1 is a top plan view of the second folding station of a multifolding machine, equipped with a preferred embodiment of this invention.

Fig. 2 is a side view, partly in elevation and partly in cross-section of the construction of Fig. 1. Fig. 2 also shows the wiring of the switch forming part of the safety device of this invention.

Figs. 1 and 2 show a once-folded sheet contacting the safety device trip plate and in position for a perforating operation.

Figs. 3 through 6 are similar to Fig. 2, and show the operation of the safety device.

Fig. 3 shows the setting of the machine and the safety device at the time a once-folded and perforated sheet is in position for a second folding operation, the perforating blade and the folding knife now being in elevated positions.

Fig. 4 shows the folding knife in a lowered folding position, a sheet in the process of receiving its second fold, and the safety device in a corresponding setting.

Fig. 5 shows the setting of the machine and the safety device when either a once-folded sheet is about to be fed to the second folding station for a perforating operation, or a sheet has failed to be properly advanced to perforating position at the second folding station and into proper engagement with the safety device trip plate.

Fig. 6 shows the setting of the machine and the safety device which follows the setting of Fig. 5 in event a sheet has failed to be properly advanced to perforating position at the second folding station and into proper engagement with the safety device trip plate. The safety device switch is in the open circuit position, the machine motor is deenergized, and the folding knife has returned to its uppermost position.

Fig. 7 is a detail view taken on line 7—7 of Fig. 1 and shows the supporting guide bar and its reciprocating mechanism in the sheet perforating position.

Fig. 8 corresponds to Fig. 7, but shows the bar and the mechanism in the sheet folding position.

Figs. 9 and 10 are respectively side and front views of a detail of the safety device of Figs. 1 through 6. Fig. 9 shows in dotted lines a second setting of the safety device trip plate and pawl.

For the purpose of illustrating a preferred embodiment of this invention, it is illustrated in the drawings as applied to the second folding

station of a conventional multi-folding machine for producing signatures of folded forms of sheets fed to and through the machine in succession and at regular machine-controlled intervals. A sheet *s* passing from the first folding station (not shown) to the second folding station has a fold at its leading edge (see Fig. 2) and is fed by tapes (not shown). These tapes and all driven parts of the machine derive their power from the shaft 5 of an electric motor 1 (see Fig. 2) according to conventional practice.

The folded sheet *s* is fed (see Figs. 1 and 2) over and on a slotted perforator bar 2, spaced folding guide bars 3, and paper supporting rods 4. Forward movement of the folded sheet *s* is arrested by guide clips 6 (see Fig. 1), which are suitably mounted on and secured to a supporting guide bar 7.

The folded sheet *s*, now in the position illustrated in Figs. 1 and 2, is ready for a perforating operation, in which a perforating blade 8 is lowered from its Fig. 2 position, passes through the folded sheet *s* and the slotted perforator bar 2, and returns to its Fig. 2 position. The perforating blade 8 at its ends is secured to the uprights 9 which are vertically reciprocated by the shaft 5 of the motor 1 through conventional mechanism (not shown).

The sheet *s*—now perforated—is shifted or advanced from the perforating position (Figs. 1 and 2) to the next (second) folding position (Fig. 3) by conventional grippers 11 (Fig. 1) according to conventional practice. The grippers 11 are supported by and secured to the supporting bar 7 similarly to the guide clips 6 (Fig. 1).

Movement of the bar 7 with its guide clips 6 and the grippers 11 is provided by mechanism shown in Figs. 1, 2, 7 and 8. The guide bar 7 is adjustably supported in conventional manner by two adjusting fingers 12, each of which has threaded engagement with a guide adjusting screw 13. Each screw 13 is supported by and axially shiftable through a bearing 14 and a box 16, both of conventional construction and secured to a stationary machine frame member 17. A hand wheel 18 on the adjusting screw 13 is provided for its adjustment. Each screw 13 is axially shifted from a forward (perforating) position (Fig. 7) to a retracted (folding) position (Fig. 8) and vice versa by the conventional mechanism of Figs. 7 and 8 which comprises a cam 21 driven from the shaft 5 of the motor 1, a bell crank lever 22, a link 23, and a two-arm lever 24.

The sheet *s* now having been folded once and also perforated, is ready for the second folding operation (see Fig. 3). A drop folding knife 26 is lowered to engage the folded sheet *s* along its line of perforations and to fold the sheet *s* by passing it through the slot between the spaced folding guide bars 3 and into engagement with the folding rollers 27 (Fig. 2). These rollers 27 pass the twice folded sheet *s* to the folding rollers 28, which in turn feed the sheet *s* to tapes (not shown) that pass the sheet to a third folding station (not shown). The drop knife 26 is secured at its opposite ends to uprights 29 which derive their vertical reciprocating motion from the shaft 5 of the motor 1 through conventional mechanism (not shown). Conventional mechanism (not shown) also transmits the drive of motor shaft 5 to the rollers 27 and 28.

The motor 1 (Fig. 2) is connected by wiring 31 to any available and convenient source of electric power. A switch, such as a double pole switch 32, may be provided in the motor circuit formed

5 by the wiring 31. When the switch 32 is placed in circuit closing position, the motor 1 is energized and provides the drive for the folding machine.

Safety device

The safety device includes a trip plate or member 41, which is pivotally supported and weighted to normally rest in an inclined position (Figs. 4, 5, 6, and 9) and to be shifted by an advancing sheet *s* to a vertical position (Figs. 1, 2, 3 and 9). In its inclined position, the trip plate 41 is disposed in the path of an advancing sheet *s*. In its vertical position, the trip plate 41 cooperates with the guide clips 6 to position properly the leading folded edge of the sheet *s*.

The trip plate 41 is pivotally secured at its opposite sides to the outer ends of two arms 42, which at their inner ends are secured to a bracket member 43. The bracket member 43 is mounted on and secured to the guide bar 7 in any suitable and conventional manner.

The trip plate 41 is provided with a fixed pin 44 that extends through an opening in the bracket member 43 for engagement with a pawl 46 pivotally secured to the bracket member 43 (Fig. 9). In the inclined position of the trip plate 41, its pin 44 frees the pawl 46 for operative engagement with a ratchet bar 47 (see Figs. 4, 5, 6 and 9). In the vertical position of the trip plate 41, it has face to face contact with the bracket member 43 (see Fig. 9), and the pin 44 positions the pawl 46 so that it is free of engagement with the ratchet bar 47 (see Figs. 2, 3 and 9).

The ratchet bar 47 extends through an opening 50 in the bracket member 43 and slidably rests on the bottom edge of such opening 50 (see Fig. 10). The lower end of the trip plate 41 is bifurcated to permit free longitudinal or end-wise movement of the ratchet bar 47 (see Fig. 10).

The ratchet bar 47 at one end is supported from one end of a spring arm 48. The other end of the spring arm 48 is supported by and secured to the machine frame member 17. The arm 48 is adapted normally to position the ratchet bar 47 in its idle position (see Fig. 2, for example), but yields to permit the ratchet bar 47 to be advanced to the open circuit position of Fig. 6 by the pawl 46 during movement of the supporting guide bar 7 from the Fig. 2 position to the Fig. 6 position. The resiliency of the spring arm 48 is effective to restore the ratchet bar 47 to the Fig. 2 position upon return of the supporting guide bar 7 to the Fig. 2 position.

The spring arm 48 carries a finger 49 for operating a weighted lever 51 of a conventional switch 52 which is connected by the wiring 31 in series relation with the motor 1. Electrically connected contacts 53 of the switch 52 are secured to and operated by the lever 51. The finger 49 and the lever 51 have a sliding contact engagement.

Under normal operating conditions of the folding machine the ratchet bar 47 remains in its idle position and the weighted lever 51 remains in circuit closing position (Figs. 2, 3, 4 and 5).

Under abnormal operating conditions of the folding machine the ratchet bar 47 is moved endwise automatically and to the left (looking at Fig. 2), and the finger 49 shifts the switch lever 51 past its dead center position and to the open circuit position of Fig. 6, where the lever 51 remains until manually returned to the closed circuit position.

Operation

When a once folded sheet *s* is about to pass to

the second fold station, the machine and the safety device are set as shown in Fig. 5. The switches 32 and 52 are set in their closed circuit positions, and the motor 1 is energized. The perforating blade 8 and the folding knife 26 are in elevated positions. The guide supporting bar 7 and the parts supported thereby are in their perforating position. The trip plate 41 is inclined, and the pawl 46 rests on the ratchet bar 47.

The once folded sheet s advances below the perforating blade 8 and the folding knife 26 until its forward motion is arrested by the guide clips 6 (Fig. 1). As the sheet s moves into engagement with the guide clips 6, the sheet s engages the trip plate 41 and swings it to its vertical position (see Fig. 2 and the dotted line position of Fig. 9). In this swinging movement of the trip plate 41, the pin 44 raises the pawl 46 to disengage it from the ratchet bar 47. The machine and the safety device now have the setting of Figs. 1 and 2, and the once folded sheet s is in position and ready for a perforating operation. The perforating blade 8 is now lowered and raised to perforate the sheet s.

The actuating mechanism (see Figs. 7 and 8) for the supporting guide bar 7 now shifts such bar 7, the parts supported thereby, and the once folded perforated sheet s to the folding position of Fig. 3. In this operation, the sheet s is gripped and advanced by the grippers 11 (Fig. 1), the pawl 46 remains disengaged from the ratchet bar 47, and the switch contacts 53 remain in closed circuit position. The machine is now ready for the second folding operation. The setting of the machine and the safety device at this time is shown in Figs. 3 and 8.

In the operation to provide the second fold in the once folded and perforated sheet s, the folding knife 26 is lowered to pass the sheet s into the space between the folding guide bars 3 and thereby initiate the folding operation which is completed by the folding rollers 27 and 28 (see Fig. 2). As the sheet s passes down through the slot between the folding bars 3, the sheet s frees the trip plate 41 and the latter under gravity action is restored to its inclined position (Fig. 4).

The mechanism of Figs. 7 and 8 restores the supporting guide bar 7 and the parts carried thereby to their perforating position of Figs. 2 and 5.

It will now be seen that as long as the sheets s are being fed properly through the machine and to the illustrated second folding station, the safety device is ineffective to open the switch 52 for the purpose of deenergizing the machine motor 1. Throughout normal operations of the machine the ratchet bar 47, the spring arm 48, the switch finger 49, and the switch lever 51 are inactive.

In the event any sheet s fails to reach the second folding station and to engage properly the trip plate 41, the latter and the pawl 46 remain in the position shown in Fig. 5 and in solid lines in Fig. 9. Thus in the next succeeding movement of the guide supporting bar 7 from the perforating position (Fig. 5) to the folding position (Fig. 6), the pawl 46 being in engagement with the ratchet bar 47 drives the latter to the switch operating position shown in Fig. 6. This movement of the ratchet bar 47 causes the finger 49 to shift the switch lever 51 which moves the contacts 53 to the open circuit position of Fig. 6.

The motor 1 is now deenergized and the machine comes to a rest.

When the misfed sheet or sheets have been removed from the machine, the motor driven parts of the machine may be reset by operation of hand wheels 56 according to conventional practice to restore the guide supporting bar 7 to its perforating position (Figs. 1 and 2). This resetting operation permits the spring arm 48 to reset the ratchet bar 47 in its idle position. The switch lever 51 is returned manually to its closed circuit position (Fig. 2). The machine is now in condition to operate as long as sheets are being fed properly and the safety device now functions as previously explained.

Other suitable and conventional switches may be used in place of the conventional switch 52. For example, the switch 52 may be provided with a spring to retain yieldingly the lever 51 in closed circuit position and to restore it automatically to closed circuit position. With such type of switch for the safety device of this invention, initial starting of the motor 1 may be accomplished by a conventional push button switch, which when closed manually is held closed by a conventional electromagnetic device connected in series with the switch of the safety device. Thus when the safety device switch is placed in open circuit position, the electromagnetic device is deenergized, the push button switch moves to open circuit position and the motor 1 is deenergized.

The foregoing is to be understood as illustrative since this invention includes all embodiments and modifications coming within the scope of the appended claims.

I claim:

1. In a sheet folding machine having a motor for driving the machine, a movable guide bar, sheet guide means carried by said bar, means carried by said bar for gripping sheets, means for perforating sheets arrested by said guide means, a folding knife intermediate said guide bar and said perforating means, and means for reciprocating said bar to advance perforated sheets gripped by said gripping means from a sheet perforating station below said perforating means to a sheet folding station in which the perforations of the perforated sheets underly said knife, the improvement comprising means including a pawl and ratchet bar, said pawl being carried by the guide bar, said pawl and said ratchet bar normally being in operative engagement with each other to transmit the sheet advancing movement of said guide bar to said ratchet bar, a device operable by said ratchet bar and adapted to control the motor of said machine, and means responsive to sheets fed into engagement with said guide means for disconnecting said pawl from said ratchet bar.
2. In a sheet folding machine having an electric motor for driving the machine, a folding knife, means for feeding sheets to a position below said knife, and a guide bar having means for arresting and positioning sheets relative to said knife, the improvement comprising a circuit for controlling the motor and including a switch, means for actuating said switch to open said circuit, and a member for controlling said switch actuating means, said member being supported by said guide bar for free swinging movement and normally in position to free said switch actuating means and to be engaged by the leading edge of a sheet advancing into engagement with said sheet arresting means and shifted by said sheet

leading edge to a second position for rendering said switch actuating means inoperative.

3. In a sheet folding machine having a drop knife for folding sheet material, means for feeding sheet material to a position below said knife, a motor for driving said machine including said knife and said feeding means, and means positioned beyond said knife for arresting sheet material passing and positioned below said knife, the improvement comprising means for controlling the operation of said motor, means for actuating said control means to thereby stop said motor, and a freely swinging member for controlling the operation of said actuating means and supported by said arresting means in the path of movement of said sheet material, said member being engageable and movable to an advanced position by the leading edge of sheet material passing below said knife and advancing into engagement with said arresting means for rendering said actuating means inoperative.

4. In a sheet folding machine having a motor for driving the machine, a knife for a first fold, a second knife for a subsequent fold, a perforator adjacent and in advance of said second knife for perforating folded sheets, means for feeding folded sheets from said first knife to said perforator, a guide bar having means for positioning sheets relative to said perforator and provided with sheet gripping means, means for reciprocating said guide bar relative to said perforator for advancing folded sheets perforated thereby to a

10
15

20

position in which the perforations of the perforated folded sheets underly said second knife, and an electric motor for driving said machine including said knives, said perforator, said feeding means, and said reciprocating means, the improvement comprising a switch for the circuit of said electric motor, a ratchet bar reciprocable to actuate said switch, a pawl mounted to travel with the guide bar and normally disposed to engage a tooth of said ratchet bar and transmit thereto the forward drive of said guide bar to actuate said switch, and a movable member operatively associated with said pawl and mounted to travel with said guide bar, said member being adapted to be engaged and moved by a folded sheet arrested by the sheet positioning means for actuating said pawl to disengage said pawl from said ratchet bar.
